DESIGN FOR AN ARTIFICIAL TREE ORNAMENT

Dorothy S. Miltenberger, Webster Groves, Mo.

Application September 21, 1936, Serial No. 64,940

Term of patent 14 years

To all whom it may concern:

Be it known that I, Dorothy S. Miltenberger, residing at Webster Groves, St. Louis County, Missouri, have invented a new, original and ornamental Design for an Artificial Tree Ornament, of which the following is a specification, reference being had to the accompanying drawing, forming part thereof.

The drawing is a perspective view of an artificial tree ornament showing my new design.

The article presents substantially the same appearance when viewed from any angle.

I claim:

The ornamental design for an artificial tree ornament, substantially as shown and described.

DOROTHY S. MILTENBERGER.
